UNITED STATES PATENT OFFICE.

WILLIAM J. MEHARY, OF PHILADELPHIA, PENNSYLVANIA.

DEVICE FOR REMOVING SNOW FROM SIDEWALKS, &c.

SPECIFICATION forming part of Letters Patent No. 275,684, dated April 10, 1883.

Application filed November 13, 1882. (No model.)

To all whom it may concern:

Be it known that I, WILLIAM J. MEHARY, a citizen of the United States, and a resident of Philadelphia, Pennsylvania, have invented 5 certain Improvements in Devices for Removing Snow from Sidewalks, &c., of which the following is a specification.

My invention consists of a machine, described hereinafter, for removing snow from sidewalks 10 and paths, the machine consisting, mainly, of a wheeled frame carrying a reservoir or tank, and having in front a scoop in which the snow ascends and falls into the tank as the machine is pushed forward, the ascent of the snow in 15 the scoop being aided by endless chains to which paddles are pivoted, as fully described hereinafter.

In the accompanying drawings, Figure 1, Sheet 1, is a side view of the machine; Fig. 2, 20 a vertical section; Fig. 3, Sheet 2, a plan view; and Fig. 4, a side view of the sweeping attachment.

The frame A of the machine is constructed to carry a box or reservoir, B, into the front end 25 of which is fitted and secured the fixed rear portion, a, of the inclined scoop D, the front portion, a', of which is arranged to be in contact, or nearly so, with the sidewalk or other path to be cleared of snow, this front portion 30 of the scoop being so connected to the fixed part of the same that it can be detached therefrom when necessary.

The machine is carried by front wheels, b, and rear wheels, d, adapted to suitable axles, 35 and through posts e of the frame, and through the fixed portion of the scoop passes a shaft, f, to which are secured the two chain-wheels G, two endless chains, H, passing round the wheels and round similar wheels, J, on a shaft, 40 h, which has its bearings in brackets i, secured to the posts k of the frame. The shaft f is driven from the wheels d in the present instance by the connecting-rods j—one on each side of the machine—one end of each rod fitting on a pin attached to the wheel or on the 45 pin of a crank on the axle, and the other end embracing the pin of a crank on the shaft f. The shaft f may, however, be driven from the wheels or axles by bands or suitable gearing. 50 Paddles K—two in the present instance—ex-

tend across the two chains to which the hubs of the said paddles are pivoted.

As the machine is wheeled forward from the rear over the path, the snow will ascend the scoop, but in the absence of the chains and paddles would present such resistance to the efforts to push the machine forward as to render this operation difficult. The paddles, however, as they are carried round with the chains, afford the desired relief, for as each paddle 60 traverses in the direction of the arrow, with its outer edge nearly in contact with the bottom of the scoop, it pushes the snow before it into the reservoir, the projecting portions m of the paddle bearing against the chains, so that it 65 cannot turn on its pivot until it passes round the pulleys G with the chains, leaving behind it in the box the snow, the ascent of which in the inclined scoop it has promoted. The box B is not secured to the frame A, but simply 70 rests thereon, so that it may be drawn rearwardly from said frame when necessary, and emptied of its contents by being overturned.

When the machine has to be converted into a sweeper to clear away such of the snow 75 as the scoop may have left on the sidewalk or path, I place the journals of a rotary brush, M, in bearings n at the rear end of the frame, and if the crank-connections above described are used, I detach the ends of the connecting- 80 rods j from the cranks of the shaft f and connect them to pins on cranks attached one to each journal of the rotary brush; or, if desired, separate connecting-rods may be used for operating the brush, as shown in Fig. 4, 85 80 the rods j in such case being detached from the operating-crank and supported by hooks or pins on the frame, as shown by dotted lines in Fig. 1. A frame, N, which is pivoted at p to the two posts e of the frame A, and which has 90 hitherto been confined by hooks to posts w in the position shown in Fig. 1, is now turned over in the direction of the arrow toward the front end of the machine, where it becomes a medium by which the machine can be pushed 95 backward when it has thus been converted into a sweeper.

I prefer to hang the rotary brush to a frame, P, which is hinged at y to the main frame, the hinged frame being provided with segmental 100

plates R, secured to the posts w by set-screws v, which pass through segmental slots in the plates, and thus permit the hinged frame, and with it the brush, to be raised or lowered at pleasure and secured after adjustment.

I claim as my invention—

1. The combination of the wheeled frame and the box with a scoop made in two parts—one fixed, the other detachable—substantially as 10 specified.

2. The combination of the scoop, chain-wheels, and chains, with paddles K, pivoted to the said chains, and having projections m, for bearing against the same.

15 3. The combination of the wheeled frame with the pivoted frame P, carrying bearings for the journals of a rotary-sweeper, and with devices by which the said pivoted frame can be

retained in different positions, substantially as described.

4. The combination of the wheeled frame, having at one end a scoop, and at the other end bearings for a brush-shaft, with the pivoted frame N, whereby the said wheeled frame can be pushed in either direction, as set forth. 20 25

5. The combination of the wheeled frame and the scoop with the box B, detached from the frame, and free to be drawn rearwardly therefrom, as set forth.

In testimony whereof I have signed my name 30 to this specification in the presence of two subscribing witnesses.

WILLIAM J. MEHARY.
